UNITED STATES PATENT OFFICE.

JOSEPH OTTNER, OF NEW BRITAIN, ASSIGNOR TO HART MANUFACTURING COMPANY, OF KENSINGTON, CONNECTICUT.

DESIGN FOR BOLT-CASE.

Specification forming part of Design No. 5,703, dated March 19, 1872.

To all whom it may concern:

Be it known that I, JOSEPH OTTNER, of New Britain, in the county of Hartford and State of Connecticut, have invented and produced a new and original Design for a Bolt-Case, of which the following is a specification:

The nature of my design is fully represented by the accompanying engraving to which reference is made.

A represents the bolt-case, and B its staple or catch. The contour of these parts is composed of straight and curved lines in the form shown. The edges of the body of the case A and staple

B are ornamented by a series of raised surfaces with rounded ends, between which are raised bars, as shown. The faces of the parts A, B are bordered by a raised ledge, inside of which is raised ornamental work. It is evident that this design is equally adapted for a cupboard catch.

I claim as my invention—

The design for bolt-case or cupboard catch, as shown.

Witnesses: JOSEPH OTTNER.
